UNITED STATES PATENT OFFICE

CHARLES W. SIRCH, OF LOS ANGELES, CALIFORNIA

OUTLET

Application filed May 14, 1927. Serial No. 191,523.

This invention relates to outlets such as used for withdrawing water from tanks. The invention is particularly applicable where the location or the character of the flow of the liquid into the outlet must be of a definite character. For example, in some industrial processes it may be necessary to withdraw liquid quietly at a predetermined level and without developing violent currents in the liquid. While the invention is applicable to such purposes, it is particularly applicable when used in connection with swimming pools. In these pools sedimentation is constantly occurring and is, of course, greatest in the lower levels of the water. My invention provides simple means for effecting the withdrawal of the water selectively, that is to say, at a predetermined level, for example, at a point just above the bottom. The general object of this invention is to provide an outlet which will meet such requirements as those outlined above; also to provide an outlet having special features of construction which adapt it for use in a swimming pool, enabling the outlet to operate in such a way as to withdraw the water at a low level and in such a way that the body of water is left relatively quiescent and undisturbed in spite of the efflux of water, thereby enabling the water drawn off to flow only, or substantially, from a certain level of the liquid. In a swimming pool, I prefer to locate the outlet on or very near the bottom and I construct it so that the water on the bottom is removed through the medium of a relatively gentle flow of currents moving into the nozzle quietly in a general horizontal direction. In this way, the layer of water having the greatest amount of sedimentation will be withdrawn and this has a constant "filtering" or separating effect on the whole body of water or other liquid.

A further object of the invention is to construct the outlet in such a way that if a lost article, such as a stocking or bathing cap, moves toward the outlet on the bottom of the tank, it will be arrested by the outlet and prevented from clogging the outlet.

Further objects of the invention will appear hereinafter.

The invention consists in the novel parts and combination of parts to be described hereinafter, all of which contribute to produce an efficient outlet.

A preferred embodiment of the invention is described in the following specification, while the broad scope of the invention is pointed out in the appended claims.

In the drawings:

Figure 1 is a plan of an outlet embodying my invention.

Figure 2 is a vertical section through the bottom wall of a tank showing the outlet partly in elevation, and with certain parts broken away and shown in section.

Figure 3 is a side elevation of the upper part of the fitting which forms a part of the outlet, the lower portion of the fitting being broken away.

In practicing the invention, I construct the outlet in such a way that the area of the mouth of the outlet is relatively large as compared with the area through the body or throat of the outlet. In this way, currents of liquid are developed flowing inwardly through the orifice or outlet which pass out of the body of liquid without causing disturbance or agitation within it. When applying the outlet to use in a swimming pool, I prefer to locate the outlet substantially at the bottom because at this point the sedimentation is greatest. By withdrawing the water at or near the level of the bottom, most of the sediment will be carried off through the outlets. This effect is augmented by constructing the outlet so as to develop a gentle horizontal flow of the liquid along the bottom into the outlet.

In order to accomplish this, I construct the outlet with a relatively large peripheral mouth or inlet which may be of relatively small dimension measured in a vertical direction. In practice, I prefer to employ a plate of relatively large diameter located over that is, superposed on the outlet, and construct the outlet so that the inlet into it occurs under the edge of this plate.

The cover plate is preferably circular and imperforate, and the admission of the liquid to the outlet occurs around the edge of the cover plate. It may cooperate with the bot-

tom to form an annular outlet. As the length of this circumferential or peripheral edge of the cover plate is relatively great, it will be evident that the velocity or movement of 5 the liquid through the outlet at this point will be relatively low. However, this will be determined by the diameter of the plate.

In the drawings I illustrate a preferred embodiment of such an outlet. This outlet includes a pipe-fitting 1 which, for convenience, 10 may be formed at its lower end into a flanged elbow 2, to which the intake pipe of a pump or a drain may be connected. This fitting may be set in the wall of the tank, for example, the bottom wall 3. The fitting may, if desired, be provided with a conical neck 4 within the bottom 3, which is formed around a throat 5 of the fitting. The upper end of the body 4 adjacent the throat 5 may be provided 15 with a plurality of laterally projecting horizontal lugs 6 formed with vertical webs 7 on their under sides. These lugs and webs are set in the concrete of the wall or bottom, and assist in preventing any movement of the fitting on its longitudinal axis through the 20 opening 8 in the bottom in which the fitting is set.

The upper end of the fitting has an extension which forms a crown 9 (see Figure 3), 30 said crown consisting of a plurality of posts 10 which are cast integral with the fitting and which extend upwardly to support an elevated ring 11 which is also cast integral with the posts.

35 On the extension 9 I support a stationary cover plate 12, said cover plate being in the form of an imperforate disk, which is preferably of circular form and of relatively large diameter as compared with the diameter of the opening 8. The edge 13 of this disk lies relatively near the upper face 14 of the wall or bottom 3 to form an annular opening of fixed width and relatively large area, 40 through which the liquid or water flows in passing into the inlet at a relatively low velocity. Where the duty of the outlet is low, the outlet may simply comprise this cover plate set over the opening. In practice, however, particularly where the outlet must pass a relatively large quantity of liquid, I mount the cover plate 12 sufficiently far from the face 14 of the bottom to permit the use of one or more intermediate stationary plates such as the plates 15 and 16. The upper plate 15 45 is held spaced from the under side of the cover plate 12 by means of lugs 17 which are cast integrally on the under side of the plate. The plate 15 is cast with similar lugs 18 on its under side. When the parts are assembled these lugs are placed in alinement with each other, and the two plates and the cover are drilled through so as to enable them to receive rivets 19, to hold the three plates together. The plates 15 and 16 are 50 preferably of annular form, with relatively

large openings 20 through them. These openings 20 are of much larger diameter than the mouth 5 and, furthermore, the opening through the bottom 3 is enlarged when it emerges and is preferably provided with an inclined or beveled face 21 over which the liquid or water passes toward the fitting. Any suitable means may be provided for attaching the plate 12 to the crown.

If desired, the cover plate 12 may simply 70 rest on the crown 9, but I prefer to provide means for centering it on the crown and for locking it to the crown. In order to accomplish this I provide the under side of the cover plate with a pair of diametrically opposite lugs 22, and in addition to this I provide two special lugs 23 which operate as interlocking means on the cover to hook under small lugs 24 which project inwardly from the posts 10. The lugs 22 and the lugs 23 75 cooperate to engage the inner sides of the ring 11 when the cover plate is set in position. After it is set in position, a slight rotation 80 on the vertical axis will interlock the hooks 23 with the lugs 24. This will lock the cover plate down on the crown. In addition to this I provide means for preventing backward rotation of the cover plate, which would 85 unlock it. This means consists of a bar 25 (see Figure 1), which is disposed diametrically under the cover plate, and this bar passes through the passages 26 which 90 are formed through the crown 9 and below the ring 11. One of its edges should be disposed against one of the lugs 22 (see Figure 1), so as to be in the path of this lug if it 95 were attempted to rotate the cover plate in a direction to unlock the hooks 23. If desired, this bar may be secured in place by 100 small screws 27, which pass down through the 105 upper plate 15.

If desired, the tapered portion of the fitting 110 may be provided with a circumferential rib or collar 30 which is imbedded in the bottom wall 3 and this operates to prevent the fitting from being dislocated in the bottom in an upward direction.

With an outlet embodying the features set forth, it will be evident that the outlet can 115 readily be adapted to special requirements. The invention readily adapted itself to use where the flow into the outlet should be very gentle. In the case of swimming pools, or tanks the outlet may, if desired, be constructed in such a way that a noticeable current or velocity of flow would be developed in a horizontal direction on the bottom, thereby assisting not only in carrying off the liquid located at a level where the sediment is greatest, but also operating to carry off sediment 120 already actually deposited on the bottom.

It is understood that the embodiment of the invention described herein is only one of the many embodiments this invention may take, and I do not wish to be limited in the prac- 125

tice of the invention, nor in the claims, to the particular embodiment set forth.

I claim:

1. In an outlet for a tank, swimming pool or the like, a bottom wall having an opening enlarged where it emerges on the upper face of the bottom, in combination with a substantially flat cover plate consisting of a stationary imperforate disk of considerably larger transverse dimension than the opening and projecting beyond the edge of the opening, so that a passage of fixed width and relatively large area is formed extending around the edge of the cover formed between the cover and the upper face of the bottom, through which the liquid flows.

2. In an outlet for a tank, swimming pool or the like, a bottom wall having an opening, enlarged where it emerges on the upper face of the bottom, in combination with a cover plate consisting of a stationary imperforate disk of considerably larger transverse dimension than the opening, so that a passage of fixed width and relatively large area is formed extending around the edge of the cover between the cover and the upper face of the bottom through which the liquid flows, and an intermediate stationary plate of annular form disposed between the face of the bottom and the said cover plate.

3. In an outlet for a tank, swimming pool or the like, a bottom wall having an opening, in combination with a cover plate consisting of an imperforate disk of considerably larger transverse dimension than the opening, said plate disposed with its edge close to the face of the bottom whereby a passage of relatively large area is formed extending around the edge of the cover through which the liquid flows at a relatively low velocity, and an intermediate plate disposed between the face of the bottom and the said cover plate, the said intermediate plate being of greater transverse dimensions than the cover plate, cooperating with the cover plate to form an annular upper passage above the intermediate plate and cooperating with the bottom to form an annular passage below the intermediate plate, said intermediate plate being of greater diameter than the cover plate whereby an object moving along the bottom will be intercepted by the intermediate plate and thereby prevented from clogging the upper passage.

4. In an outlet for a tank, swimming pool or the like, a bottom wall having an opening, in combination with a cover plate consisting of an imperforate disk of considerably larger transverse dimension than the opening, said plate disposed with its edge close to the face of the bottom whereby a passage of relatively large area is formed extending around the edge of the cover through which the liquid flows at a relatively low velocity, and a pair

of intermediate plates disposed one above the other between the face of the bottom and the said cover plate, the upper of said intermediate plates being disposed slightly below the cover plate and cooperating with the same to form an upper annular passage for the liquid, the lower of said intermediate plates lying close to the face of the bottom and cooperating with the same to form a lower annular passage for the liquid, the lower of said intermediate plates being of larger diameter than the upper plate whereby an object moving along the bottom toward the outlet with the liquid will be intercepted by the lower plate and thereby prevented from clogging the upper passage.

5. In an outlet for a tank, swimming pool or the like, a bottom wall having an opening, in combination with a fitting mounted in the opening, a stationary cover plate detachably secured to the fitting and consisting of an imperforate disk of considerably larger diameter than the opening located close to the face of the bottom whereby an annular passage of fixed width and relatively large area is formed between the under face of the disk and the upper face of the bottom around the edge of the plate through which the liquid flows at a relatively low velocity.

6. In an outlet to be mounted in the bottom of a tank, swimming pool or the like, the combination of a bottom having an enlarged opening emerging on its upper face, a pipe-fitting having a mouth at its upper end having an extension forming a crown near the said mouth, a cover-plate supported on said crown, said crown and said cover-plate having interlocking means operating to lock the cover-plate to the crown by a rotary movement, said cover-plate being of relatively large diameter with respect to the said mouth, projecting over the edge of the opening in the bottom, lying close to the bottom and cooperating with the bottom to form an annular outlet opening.

7. In an outlet to be mounted in the bottom of a tank, pool or the like, the combination of a pipe-fitting having a mouth at its upper end and having a crown near the mouth, including an elevated ring with posts supporting the same from the fitting adjacent the mouth, whereby lateral ports are formed through the crown to admit water to the mouth, a stationary cover plate supported on the ring of said crown consisting of an imperforate disk of relatively large diameter with respect to said mouth, and operating when in position to lie close to the face of the bottom and form a narrow outlet opening of fixed width.

8. In an outlet to be mounted in the bottom of a tank, pool or the like, the combination of a pipe-fitting having a mouth at its upper end and having a crown above the mouth, including an elevated ring with ports formed

through the crown below the ring to admit water to the mouth, a cover plate supported on the said crown consisting of a stationary imperforate disk of relatively large diameter with respect to the said mouth, and operating when in position to lie close to the face of the bottom, and a bar passing through the ports below the said ring and secured to the under side of the cover plate to hold the same in fixed position.

9. In an outlet to be mounted in the bottom of a tank, pool or the like, the combination of a pipe-fitting having a throat at its upper end and having a crown near the throat, including an elevated ring with posts supporting the same from the fitting adjacent the throat, whereby lateral parts are formed through the crown to admit water to the throat, a cover-plate supported on the ring of said crown consisting of an imperforate disk of relatively large diameter with respect to the said throat, and operating when in position to lie close to the face of the bottom, interlocking means between the ring and the under side of the cover plate for locking the cover plate to the ring by rotary movement, and a bar extending through the ports below the said ring and operating to prevent rotation of the cover plate in a direction to unlock it from the ring.

10. In a bottom outlet for a tank, swimming pool or the like, a pipe fitting having a crown at its upper end with side openings and an elevated centrally disposed ring, a cover plate resting on the said ring and consisting of a stationary imperforate disk extending laterally from the fitting, and a lower plate of disk form supported from the cover plate and disposed near the under face of the cover plate whereby an annular passage of fixed width is formed for the water around the edge of the plate between the lower plate and the upper face of the bottom.

11. In an outlet for a tank, swimming pool or the like, the combination of a bottom having an opening enlarged where it emerges on the upper face of the bottom, a pipe fitting extending through the opening having an inlet mouth and a substantially flat cover plate consisting of a stationary imperforate disk supported over said mouth with its edge projecting over the edge of said opening and having its under face disposed in a plane and substantially horizontal so that a passage of fixed width is formed for the liquid extending round the edge of the cover and formed between the plate and the bottom.

Signed at Los Angeles, Calif., this 6 day of May, 1927.

CHARLES W. SIRCH.
